DESIGN FOR A MUSICAL INSTRUMENT SIMILAR TO AN OCARINA

Ziegner Swanson, De Kalb, Ill.

Application September 26, 1938, Serial No. 80,095

Term of patent 14 years

To all whom it may concern:

Be it known that I, Ziegner Swanson, a citizen of the United States, residing at De Kalb, in the county of De Kalb and State of Illinois, have invented a new, original, and ornamental Design for a Musical Instrument Similar to an Ocarina, of which the following is a specification, reference being had to the accompanying drawing, forming part thereof.

In the drawing:

Fig. 1 is a top plan view of a musical instrument similar to an ocarina showing my new design.

Fig. 2 is a side elevation of the same.

Fig. 3 is a bottom plan view of the same.

Fig. 4 is an end view of same.

I claim:

The ornamental design for a musical instrument similar to an ocarina, as shown.

ZIEGNER SWANSON.
